UNITED STATES PATENT OFFICE

WILLIAM A. DARAH, OF CHICAGO, ILLINOIS

HEAT-TREATING MACHINE

Application filed June 4, 1927. Serial No. 196,584.

This invention relates to equipment and methods of heat treating material and is particularly applicable to the heat treating of steel or alloys in that it permits a very uniform distribution of heat with a high degree of economy.

One application of this device is the so-called drawing or tempering of steel parts. In general, however, it may be stated that this equipment may be useful wherever it is desired to controllably and uniformly heat any substance to a specific temperature and maintain it at that temperature for an appreciable time.

15 Referring to the drawing:

Fig. I shows a vertical side elevation in section of one form of my device;

Figure II shows a top plan view partly in section of the same equipment;

20 Fig. III shows a horizontal section along the line AA;

While Fig. IV shows an end elevation of the device illustrated in Fig. I;

Fig. IV is shown partly in section;

25 Fig. V shows another horizontal section of the device the section in this case being taken along line BB;

Fig. VI shows a detail of one form of basket which may conveniently be used with this equipment.

The equipment consists of a frame or spider (1) supported at its upper portion on a flange or rim (2) provided with a circular groove (3) arranged to roll over a series of balls (4), 35 a coacting circular member (5) is located beneath the balls (4) and serves as a runway or track to confine them. A series of teeth or the equivalent (6) is provided in flange (2) and arranged to engage with a driving member (7) which is mounted on shaft (8) and may be driven from pulley (9) or by any other desired means. Shaft (8) is shown turning in bearing (10) which is supported by bracket (11) attached to the outside frame or 45 housing (12).

The housing (12) incloses an insulation or semi-refractory material (13) which is molded in such a manner as to provide a series of flues for purposes later to be described. In one portion of the refractory ma-

terial (13) is molded a container or housing (14) containing a fan wheel (15) which may be driven in any desired manner as for example by motor (16).

A flue portion (17) terminating near the intake of fan (15) serves to deliver circulating gases to the fan chamber (14). The operation of the fan forces these gases out through outlet (18).

In the course of their travel the gases pass through a constriction or Venturi throat (19) and then to distributing duct (20). Distributing duct (20) is arranged to deliver circulating gases in such a manner that they travel substantially horizontally through the spider member (1) and also through a basket member (21) which is carried by said spider member (1). The basket member (21) is preferably made from perforated or expanded material or mesh in such a manner that it will hold the articles being treated without allowing them to fall out, but will at the same time permit the ready passage of the circulating gases through the basket and into contact with the material being treated. After passing through the material being treated the circulating gases leave by duct (22) which connects to flue (23) which in turn delivers the gases to flue (17) and thus to the intake of the circulating fan or blower.

The arrows shown the direction of travel of the circulating gases which it will be noted is continuous in a single direction and of substantially constant volume depending upon the resistance interposed in their path.

A combustion chamber (24) constructed of proper heat resisting materials is located convenient to the circulating gases and provided with a discharge flue (25) leading to the throat or constriction of venturi (19). An alternative flue connection (26) is shown by the dotted lines as leading from the discharge chamber to the intake of the fan (17). Obviously under ordinary conditions either flue (25) or flue (26) would be employed and the one not employed would be closed. Certain advantages result from the use of each as will later be described.

Burners (27) and (28) are provided to deliver fuel to the combustion chamber. The

fuel may be gas, oil or the desired equivalent. The burners may be controlled by thermostatic valve (29) preferably operated from a thermostat (30) inserted in the discharge passage of the circulating gas. Thermostat (30) serves to maintain the temperature of the gas leaving the circulating fan at any desired constant value.

The housing (12) is to be provided with a cover (31) which may be operated in any desired manner as for example, by handle (32) pivoted on bearing (33) and provided with counterweight (34) to permit easy adjustment.

In the course of operation of this device, it will be apparent that when motor (16) is started in rotation a continuous circulation of gases will take place as described following the general direction of the arrows.

When the burners (27) and (28) in combustion chamber (24) are lighted, it will be noted that the products of combustion are drawn into the circulating gases either by the reduced pressure resulting from the Venturi throat (19) or through the intake of the blower (17) passing in this case through flue (26).

It will be noted that when the products of combustion travel through flue (26) into the intake of the blower the blower will be required to handle circulating gases at the maximum temperature of the device, while on the other hand, if the products of combustion pass through flue (25) instead of through flue (26) the blower will be required to handle circulating gases at the minimum or returned temperature.

An exhaust flue (35) provided with a self-closing valve (36) provides for the discharge of excess gases, thus preventing an accumulation of pressure in the system owing to the continual addition of products of combustion.

It will be evident that thermostat (30) will regulate the quantity of fuel supplied by burners (27) and (28) thus insuring a constant uniform temperature of the circulating gases when they pass through basket (21) and into contact with the material therein.

It will also be apparent from the description given that as basket (21) is rotated by means of spider member (1) and the mechanism previously described, all parts will be continuously subjected to substantially uniform treatment by the hot blast of circulating gas, thus giving a highly uniform distribution of heat throughout the mass of material within the basket.

Owing to the fact that the products of combustion are directly retained and mixed with the circulating gases very high degrees of efficiency may be secured with this equipment.

It will be apparent that many obvious substitutions may be made without departing

from the spirit of this invention. For example, the basket may be constructed in any form or shape or in place of the basket I may employ a horizontal tube or I may prefer to allow the basket to remain stationary and depend on the movement of the air only, which I have found gives quite satisfactory results in many cases. Obviously the basket may be supported from a plate placed beneath it or in any other desired manner without departing from the spirit of this invention.

I have found in actual practice that equipment of this kind will serve to heat articles to the desired temperature with great accuracy and uniformity. That is to say by maintaining the circulating air at a given temperature no articles can, under any conditions, be heated higher than the temperature of the circulating air. Obviously this is a decided advantage over the performance of furnaces which depend partly upon radiant heat for thermal transfer. Such furnaces are subject to considerable over heating of some articles and under heating of other articles.

It will also be apparent that since the products of combustion are held in the circulating gases and therefore come in contact with the substances being heated, the efficiency must be very high.

In referring to a heat treating machine, I wish it to be understood that I am referring to any device in which heat is applied to accomplish a useful result. Thus I intend the term to cover such operations as roasting, drying, baking, annealing, carburizing, cooking, boiling, melting, etc., as obviously this equipment will find a wide field of application wherever a uniform and controlled temperature is required.

While I have shown a specific type of gas moving mechanism or blower, it will be understood that any satisfactory mechanism which will keep the gases in motion may be used. Further I do not wish to be restricted to any particular shape or design of container as this will obviously be varied to suit the operations being carried out. In some cases the container may be closed as for example in heating very small articles or powders. Any desired fuel may be employed and by the term "combustion chamber" I intend to indicate the space or inclosure where the combustion takes place or the products of combustion are concentrated.

Having now fully described my invention what I claim as new and wish to secure by Letters Patent in the United States, is as follows:

1. A device for heat treating consisting of a container, a support for said container, a gas circulating device, flues leading from said gas circulating device to said container, flues leading from said container to said gas

- circulating device, a combustion chamber, means for conducting the products of combustion from said combustion chamber into said gas circulation system at a position on the discharge side of said gas circulating device, and an exhaust outlet for permitting the escape of an excess of circulating gases, said exhaust opening being located on the discharge side of said gas circulating device.
2. A heat treating machine comprising a container, supporting means for said container, a mechanism for moving said container, a complete gas circulating system passing from a gas moving mechanism through said container and back to said gas moving mechanism, a combustion chamber, and a flue connecting said combustion chamber with a portion of the discharge of said gas moving mechanism, at a point of reduced sectional area.
3. A heat treating machine comprising a container, a support for said container, a gas moving mechanism, a flue leading to said container from said gas moving mechanism, a combustion chamber, and a flue making connection between said combustion chamber and the discharge flue connecting said gas moving mechanism and said container, said connection being at a point of reduced sectional area in said first mentioned flue.
4. A heat treating machine comprising a container, a support for said container, a gas moving mechanism, a flue leading from the discharge portion of said gas moving mechanism to said container, a flue leading from said container to the intake of said gas moving mechanism, a combustion chamber, said discharge flue from said gas moving mechanism having a constricted portion, and a connection between said combustion chamber and said constricted portion of said discharge flue.
5. A heat treating machine comprising a container, a support for said container, a gas moving mechanism, a flue of varying section connecting the discharge of said gas moving mechanism to said container, a flue connecting said container to the intake of said gas moving mechanism, a combustion chamber partly surrounded by said flues, and a connecting flue between said combustion chamber and said discharge of said gas moving mechanism.
6. A heat treating machine comprising a container, means for moving said container, a gas moving mechanism, a combustion chamber, flues connecting said container with said gas moving mechanism and said combustion chamber with the discharge of said gas moving mechanism and an exhaust means for the escape of excess gases.
7. A heat treating machine comprising a container, a support for said container, a gas moving mechanism, a flue of varying effective cross section leading to said container
- from said gas moving mechanism, a combustion chamber and a flue connecting said combustion chamber to the discharge portion of said gas moving mechanism.
8. In a heating device a combustion chamber, a gas moving mechanism, and a chamber to be heated, flues connecting said chamber to be heated and said gas moving mechanism, and a flue of varying effective section connecting said combustion chamber with the discharge portion of said gas moving mechanism.
9. In a heating machine a gas moving mechanism having a discharge portion of varying cross-section to form a venturi, a combustion chamber and a connection between said combustion chamber and the reduced pressure portion of said venturi.
10. In a heating machine a gas moving mechanism having a discharge portion of varying cross section to form a venturi, a combustion chamber and a connection between said combustion chamber and the reduced pressure portion of said venturi, and an exhaust outlet connected to the discharge portion of said gas moving mechanism.
11. In a heating machine, a chamber to be heated, a gas moving mechanism having a discharge portion of varying cross section to form a venturi, connected to said chamber to be heated, a combustion chamber and a connection between said combustion chamber and the reduced pressure portion of said venturi.
12. In a heating machine, a chamber to be heated, a gas moving mechanism having a discharge portion of varying cross section to form a venturi, a combustion chamber and a connection between said combustion chamber and the reduced pressure portion of said venturi, a connection between the discharge of said venturi and said chamber to be heated, and a connection between said chamber to be heated and the intake of said gas moving mechanism.
